TARGET TYPE TOY WITH PIVOTED TARGETS

George F. Haiselup, Indianapolis, Ind.

Application July 20, 1949, Serial No. 105,879

6 Claims. (Cl. 46—1)

1

This invention relates to a toy structure.

The chief object of the present invention is to provide a toy having a plurality of spaced longitudinally aligned targets which are so arranged and constructed that they may be progressively toppled when the foremost target is struck or so that they may be toppled in succession independently of each other.

It is a further object of the present invention to provide a toy of such construction that the targets may readily and substantially simultaneously be moved to an upright position after they have been toppled either progressively or successively.

The chief feature of the present invention resides in the construction of the targets and a mounting thereof upon a base in such manner that they may readily be moved to an upright position in a simple, easy fashion after having been toppled.

An additional feature of the present invention resides in the construction of the base upon which the targets are mounted so that a plurality of bases may be inter-connected to provide a much longer row of targets, which targets may then be toppled progressively or individually and successively, as desired.

Other objects and features of the invention will be set forth more fully hereinafter.

The full nature of the invention will be understood from the accompanying drawings and the following description and claims:

In the drawings,

Fig. 1 is a perspective view of a single unit with the obstacles or targets thereof shown in erected position by full lines and one of them in the knocked down position by dotted lines, intermediate parts being broken away and omitted.

Fig. 2 is a top plan view of the interconnection between two adjacent ends of a plurality of units arranged for simultaneous operation, the forward unit tension spring being removed.

In the drawings 10 indicates an elongated base having upwardly directed sides 11 disposed substantially parallel to each other. Usually the base and sides comprise a light metal channel, the sides of which can be slightly sprung for reasons set forth later.

The two sides are provided with spaced holes 12, the opposite holes being aligned for pivot purposes. The obstacles or targets may partake of any desired outline or conformation, and each comprises a main body portion 13 that terminates at its lower end 14 in a base plate portion 15.

Extending oppositely the side edges of each 55

2

base 15 and in longitudinally aligned relation are the tongues 16, each pair thereof being selectively receivable by a pair of opposed aligned openings or holes 12. Thus each target is pivotally mounted upon the channel base.

When disposed in erected position, the body portion is substantially vertical with respect to the base 10, and the end 14 and the base 15 are at a suitable angle to each other and rest upon the base 10. The successive pairs of holes 12 are so spaced apart that the upper end of the target when it is falling down, engages the target back of it and knocks it down and so on.

When a target is disposed in knocked down position, its upper end will rest upon the lower end of the adjacent target (see dotted lines in Fig. 1). When the targets are thus disposed all will fall down progressively when the foremost target is hit by a projectile, ball, etc., or tapped with the finger.

Note that the center of gravity of the target lies forwardly of the pivotal axis, even though it be canted rearwardly to a slight degree. Thus the target, while readily tipped rearwardly is normally constrained to the erected position after having been tilted upwardly and forwardly past center from the knocked down position.

Each target near bottom 14 includes a small but elongated aperture 17. Strung through all apertures, which are aligned fore-and-aft, is the cord 18. The rear end of this cord is suitably connected as by snap hook 20 to one end of a spring 19. The other end of said spring is suitably anchored to hook portion 21 formed in and upon base 10. Thus the cord is normally constrained rearwardly.

The other end of the cord 18 is suitably secured to a grip member 22, such as a ball. Herein the side walls 11 terminate short of the end of base 10. The forward end of that base is turned upwardly approximately ninety degrees to form tongue 23. It is spaced from the forward edges of walls 11 for a purpose to be described. The tongue 23 is apertured at 24 to receive cord 18.

Once all of the targets have been toppled to a reclining position the juncture of the base and body portion of each target will be positioned in a plane above aperture 24. The base portion 15 of the target will then be inclined forwardly of the vertical to a slight degree. Since the cord is secured to the base 10 in a plane below the plane of the apertures 17, it naturally follows that when the cord is pulled forwardly and thereby tautened, the targets will be elevated.

substantially simultaneously to an upright position.

When single impact progressive target dropping is not desired, the snap hook 20 is disengaged from the spring and a suitable number of the targets are sprung from the side walls and removed, the elongated apertures 17 passing said hook 20.

Then the front target is left as before and each succeeding target in effect is displaced rearwardly and the tongues 16 thereof are positioned in the second series of holes 25 in said side walls.

Now when the first target is struck only the first target falls. Since the length of the target body is insufficient to effect contact with the second target, the successive targets remain erect. Thus each target must be knocked down individually. However, by pulling upon cord 18 all targets will be erected by one pull provided the snap hook 20 has been reconnected to the spring.

Reference will now be had to Fig. 2. Herein the adjacent ends of two units are illustrated in interconnected relation. Herein the rear end of the forward of the two units has its base portion 10 provided with a T-shaped slot 26 immediately rearward of hook 21. This slot has its bar portion disposed transverse to the base 10 and its stem portion disposed longitudinally thereof, the latter portion terminating at the end of the base 10.

In order to interconnect two units the following procedure is followed: The end of the cord having a ball secured thereto is first looped rearwardly over the tongue 23 disposed at the forward end of each unit. The tongue is then passed upwardly through the slot 26. The stem of the slot will permit the cord to pass therethrough to the position shown in Fig. 2. If that stem were not provided it is obvious that the cord would be looped under the end of the base 10 and would not be operable. Next the snap hook 20 adjacent said slot is disengaged from its spring and snapped upon the cord 18 immediately behind the ball secured thereto. As a result of this connection a pull upon the ball disposed at the front end of the forward unit of the two units will erect all targets substantially simultaneously.

While the invention has been illustrated and described in great detail in the drawings and foregoing description, the same is to be considered as illustrative and not restrictive in character.

The invention claimed is:

1. A target type toy unit comprising a base having upstanding side walls, a plurality of spaced longitudinally aligned substantially L-shaped targets each having a base portion and an upright portion, said base portions being pivotally connected adjacent their free ends to said side walls, said upright portions having an aperture formed therethrough above the respective junctures of said base and upright portions, and a cord member connected to the rearward end of said base and normally extending loosely through said respective apertures, whereby said targets may be elevated from a knocked down to an upright position by a pull upon the free end of said cord.

2. A target type toy unit comprising a channel type base having upstanding side walls substantially coextensive therewith; a plurality of longitudinally aligned substantially L-shaped targets each having a base portion and an upright portion, said base portions each being pivotally con-

nected adjacent their free ends to said side walls a distance less than the length of an adjacent target when in its knocked down position, said upright portions each having an aperture formed therethrough above the juncture of said base and upright portions, and a cord member connected to one end of said channel base and extending longitudinally thereof through said respective apertures, whereby said targets may be elevated from a knocked down to an upright position by a pull upon the free end of said cord.

3. A target type toy unit comprising a channel type base having upstanding side walls, a plurality of spaced longitudinally aligned targets each having a base and an upright portion disposed in slightly less than right angular relation, said base portions being pivotally connected at a point remote from the juncture of said base and upright portions to said side walls, said base portions being inclined forwardly of the vertical when said targets are in their knocked down position, said upright portions each having an aperture formed therethrough above said juncture, resilient means connected to the rearward end of said channel base, and an element connected to said resilient means and normally extending longitudinally through said respective apertures, said element being biased by said means to one position and being manually movable against the constraint of said means to another position whereby said targets may be elevated from a knocked down to an upright position.

4. In combination, a plurality of target type toy units adapted for interconnection one to the other, each of said units comprising a channel type base having spaced side walls, a plurality of spaced longitudinally aligned targets each having a base portion and an upright portion disposed in slightly less than right angular relation, said base portions each being pivotally connected at a point remote from the juncture of said base portion and said upright portion to said side walls, said base portions being inclined forwardly of the vertical when said targets are in their knocked down position, said upright portions each having an aperture formed therethrough above said juncture, a cord member having a means detachably connected to the rearward end of each channel base, said member extending longitudinally through said respective apertures, an upstanding tongue formed at the forward end of each of said units, and a complementary T slot formed at the rearward end of each of said units, the bar portion of said slot being disposed transverse to said channel base and the stem portion thereof terminating at the end of said channel base, whereby said units may be interconnected.

5. In combination, at least two target type toy units adapted for interconnection one to the other, each of said units comprising a channel type base having spaced side walls, a plurality of longitudinally aligned substantially L-shaped targets each having a base portion and an upright portion, said base portions being pivotally connected adjacent their free ends to said side walls, said upright portions each having an aperture formed therethrough above the juncture of said base and upright portions, a cord member having means for detachable connection to the rearward end of each channel base, said member normally extending loosely through said respective apertures, an upstanding tongue formed at the forward end of said channel base, and a com-

plementary T slot formed at the rearward end of said channel base, the bar portion of said slot being disposed transverse to said channel base and the stem portion thereof terminating at the end of said channel base, whereby said units may be interconnected.

6. A target type toy unit comprising a base having upstanding side walls, a substantially L-shaped target having a base portion and an upright portion, said base portion being pivotally connected adjacent its free ends to said side walls, said upright portion having an aperture formed therethrough above the juncture of said base and upright portions, and a cord member connected to the rearward end of said base and normally extending loosely through said aperture,

whereby said target may be elevated from a knocked down to an upright position.
